CLAIM

The ornamental design for a mobile phone, as shown.

DESCRIPTION

FIG. 1 is a rear elevational view of a mobile phone showing our new design;

FIG. 2 is a left side, elevational view thereof;

FIG. 3 is a right side, elevational view thereof;

FIG. 4 is a top plan view thereof; and,

FIG. 5 is a bottom plan view thereof.

The broken lines throughout the views, which are immediately adjacent to the shaded areas and define unshaded regions, represent the bounds of the claimed design, while all other broken lines are directed to environment and are for illustrative purposes only; the broken lines form no part of the claimed design.
